(57) **CLAIM**

The ornamental design for an evans calcaneal bone wedge, as shown and described.

DESCRIPTION

FIG. 1 is a front perspective view of the evans calcaneal bone wedge comprising the new design;

FIG. 2 is a side perspective view of the design of FIG. 1;
FIG. 3 is a front elevational view of the design of FIG. 1;
FIG. 4 is a sectional view along line 4-4 of FIG. 3 of the design of FIG. 1;

FIG. 5 is a top view of the design of FIG. 1;

FIG. 6 is a right elevational view of the design of FIG. 1, where the left side elevational view is a mirror image;
FIG. 7 is a rear elevational view of the design of FIG. 1; and,
FIG. 8 is a bottom view of the design of FIG. 1.
